UNITED STATES PATENT OFFICE

2,457,557

PROJECTOR FOR LIQUID AND PULVERULENT OR SMALL MATERIAL

George Seymour Higginson, Ilford, England, assignor of one-half to Guy Stedman May Ashby, Hermitage, England

Application September 22, 1944, Serial No. 555,364
In Great Britain September 24, 1943

12 Claims. (Cl. 259—18)

1

The primary object of the present invention is to provide a projector or mixer for liquids and for pulverulent, granular, powdered and like divided material, such as pulverulent fuel or small fuel, wherein thorough atomisation or fine disintegration and dispersal and mixing of liquid throughout the volume of a projected jet and thorough dispersion and mixing of pulverulent and other divided material throughout the volume of a projected jet is obtained.

According to the invention jets consisting of the material to be projected and air, various gases or steam are directed towards each other directly or relatively obliquely so that the particles of material in the jets collide and bounce relatively whereby they are caused to disperse throughout the volume of the combined jet resulting from the meeting of the opposed jets. When the said material comprises or consists of liquid liquid particles are formed in the original jets and when the particles in the opposed jets collide they are further disintegrated or atomised. To a lesser degree division of solid particles, such as agglomerated particles, occurs when the particles collide at the confluence of the jets and immediately thereafter. The zone at which the jets meet may be in a chamber having an outlet orifice for the combined jet. The shape of the orifices defining the opposed jets and the shape of a nozzle defining the final jet if the latter nozzle be provided, are preferably such that the final jet is substantially flat with divergent sides.

The invention also comprises a projector for liquid material and/or for pulverulent or small material, comprising a cylindrical rotor in which are a number of angularly spaced, longitudinal pockets, said pockets being adapted to receive the material to be projected, and valve means adapted to supply pressure fluid to each pocket in the vicinity of the bottom thereof substantially throughout the whole of the length thereof when the pocket attains a predetermined position during turning of the rotor whereby the pockets are successively emptied of their contents by the pressure fluid.

A projector for carrying out the above method according to the invention comprises two or more of the cylindrical rotors, said rotors being set to direct their jets in opposed or convergent directions and being so timed relatively that the discharge of the contents of a pocket of each occurs simultaneously whereby the resulting, simultaneously occurring jets impinge on each other.

The invention has many industrial applications where liquid and/or powdered or like material is

5 required to be projected or sprayed. For example, a projector according to the invention may be adapted to operate as a burner for liquid, pulverulent (or small) or colloidal fuel (an oil and pulverised fuel mixture) or for a mixture of fuels such as anthracite dust and bituminous fuel.

When the projector is used as a burner the particles of the final jet introduced into a hot furnace are immediately gasified and ignited 10 owing to their being freely dispersed throughout the jet and are completely burnt or nearly so by the time they sink to the furnace bottom. Primary air for the combustion is supplied with the fuel when air is used wholly or partly as the fuel 15 impellant for one or both of the opposed jets and secondary air is introduced into the furnace preferably at low velocity in any suitable manner, for example, secondary air may flow into the furnace through the bottom thereof. When steam is 20 used wholly or partly as the impellant water gas may be formed in the furnace and is ignited. Primary air and/or steam may be supplied through a nozzle independently of the fuel.

The jets may be continuous or intermittent. In 25 most cases they will be intermittent. The jets may be flat, round or of other suitable cross section and the final jet is preferably substantially flat with divergent sides.

In manufacturing quicklime, cement and the 30 like, reducing metallic oxides and carbonising coal the limestone, oxide or coal is projected in finely divided form into the chamber in which the requisite treatment is to be effected, said chamber being hot and air, gas or steam that may 35 be necessary for the treatment is either included in one or both or more of the original jets or is introduced into the treating chamber by one or more nozzles separate from the projector. An important feature of such treatment may include 40 the provision of such a temperature in the treating chamber that the particles, being dispersed throughout the volume of the combined jet, are exposed on all sides to the heat with the result that they explode or disintegrate, thus being 45 further finely divided. In some cases one or more jets may comprise limestone, for example, and another or others coal.

The invention will now be described with reference to the example illustrated in the accompanying drawings wherein:

Figs. 1 and 1a together show a sectional elevation of a two-rotor projector, the plane of section approximately coinciding with the vertical median plane thereof;

Fig. 2 is a plan view;

Fig. 3 is a view of the projector from the pressure fluid inlet end thereof; and

Figs. 4, 5 and 6 are sectional end views in the planes indicated by the lines IV—IV, V—V, and VI—VI, Fig. 1.

The projector comprises a part-cylindrical case 1 in which are two longitudinal bores 2, 3, one above the other, which meet at the longitudinal axis of the cylinder, the axes of the bores being in the vertical plane containing this axis. The case has two mouths 4, 5 intermediately of its ends, which mouths communicate with the bores 2, 3, respectively, and at the side substantially opposite to that in which the mouths are formed has a divergent discharge opening 6 communicating at its narrowest part with the lower portion of the upper bore 2 and the upper portion of the lower bore 3. The ends 7 of the said opening 6 are also divergent as will be clear by reference to Fig. 2 and are between the ends of the said case.

Within the case 1 is a liner 8. The case and the liner may be bolted together or 1 may be shrunk onto 8. The liner fits within the bores 2, 3 and within the narrowest part of the opening 6. It has longitudinal openings 9 and 10 communicating with the inner ends of the mouths 4 and 5, respectively, a divergent opening 11 registering with the opening 6 from end to end thereof, part of the walls of the opening 11 lining the narrower part of the said opening 6, and two longitudinal slots 12 and 13 at the throat of the opening 11. The slots 12 and 13 are about as long as the said throat; they are substantially radial with respect to the axes of the respective bores and converge towards each other—as will be clear by reference to Fig. 4.

The opening 11 and the material of the liner 8 defining it form the main discharge nozzle of the projector. The slots 12 and 13 and the material of the liner defining them form elemental nozzles which discharge into the throat of the main discharge nozzle, the general direction of the elemental nozzles being slightly inclined towards the wider or discharge end of the main nozzle.

The rotors, which are substantially alike, are indicated at 15 and 16. Each comprises a central part 17 which is a tolerance fit in the liner in a bore 2 or 3, reduced end portions as 18, 19 which lie between the said central part and valve plates 19 and 20, and further reduced end portions 21 which extend through the valve plates and through bearings as 22, said bearings supporting the rotors. The valve plates are circular and lie in the bores of the lining 8. The bearings are mounted in end plates 23, 23—24, 24, which butt against the valve plates and are secured to the liner 8 by screws 25.

One reduced end 21 of each rotor extends well beyond its corresponding bearing 22 and has a toothed wheel 26 affixed. The two wheels 26 intermesh; one of them meshes with a spur wheel 27 rigid with a worm wheel 28. Bearings 30 carried by a spigot 31 support the wheels 27 and 28. A worm 32 meshing with the wheel 29 is adapted to drive the latter, the worm shaft being mounted in bearings carried by an end cap 33 secured to the case 1. The said end cap has a web 34 which is suitably apertured to accommodate the hubs of the wheels 26; and the spigot 31 is mounted on this web, the mounting comprising fixing screws 35. The end 36 of the worm shaft is adapted to be coupled to any suitable driving means, not shown, such as an electric motor. Thus, when the worm is rotated the rotors are turned in oppo-

site directions by the toothed wheels 26. In practice the worm drive is such that the rotor 15 turns clockwise and the rotor 16 contra-clockwise (Fig. 4).

The pockets provided in the rotors are indicated at 37. The sides of each pocket are divergent, the bottom is rounded and the mouth is in the surface of the rotor. The median planes of the pockets are tangential to a small imaginary circle having its centre in the rotor axis, the inclinations of the said planes being such that the mouths of the pockets are in advance of the rounded bottoms thereof in the direction of rotation. The ends 38 of the pockets diverge slightly as clearly shown in Figure 1.

The portion of each rotor lying between the valve plates 19 and 20 is longitudinally bored and slotted to provide conduits 39 one for each pocket. The slotted portions of the conduits open to the said pockets along the whole of the bottom of the latter whilst the ends of the said conduits face the valve plates. These conduits enable pressure fluid to be introduced into the pockets at the bottoms thereof.

The pressure fluid is controlled in the first instance by a plug valve or the like 40 mounted on an end cap 41 secured to the case 1. The valve has two inlets 40^a, 40^b for pressure fluid and is preferably of a type such that fluid from either inlet can be supplied to the pockets or fluid from one inlet can be supplied to the pockets of one rotor and fluid from the other inlet to the other rotor. Thus, if different fluids are used, such as air and steam, air may be supplied to the pockets of either rotor and steam to the pockets of the other rotor or either of these fluids may be supplied to both rotors.

The valve outflow passages are indicated at 42 and 43. The outer ends of the passages directly 40 communicate with chambers 44 in the end plates 23, and communicate with chambers 45 in the end plates 24 by way of lateral bores 46 and 47 in the said end plates, tubes 48 on the end caps 41 and 33 and longitudinal bores 49 in the liner 8.

Each valve plate has two chambers 60 and 61 communicating with each other by way of inclined bores 62 in the said plates. The chambers 60 in the valve plates 19 communicate with the chambers 44 by way of passages 63 in the end plate 23 and the chambers 61 in the valve plates 20 communicate with the chambers 45 by way of passages 64 in the end plate 24.

It will now be clear that all chambers 44, 45 and 60, 61 are kept charged with pressure fluid when the valve 38 is opened. In order to prevent the escape of this fluid between the plug 65 of the valve and the end plates 23, between the end plates and the adjacent valve plates, between the valve plates and the reduced ends 18 of the rotor 60 and at joints between the conduits 46 and the tubes 48 and between the tubes and the bores 49, the said chambers and the said joints are provided with sealing cups as 66. The bases of the cups are forced against the plane faces of the adjacent members and the walls are expanded into contact with the sides of the chambers by the pressure of the fluid in the chambers receiving the cups, thereby preventing leakage.

The chambers 61 are so located that the conduits 39 in the rotor 15 successively register with the said chambers in the upper valve plates and the conduits in the rotor 16 successively register with the chambers in the lower valve plates as the rotors turn so that the said conduits successively receive charges of pressure fluid which

they conduct to the bottoms of their pockets along the whole of the length thereof. Moreover, the location of the chambers 61 is such that the pockets which so receive charges of pressure fluid are the pockets in register or about to register with the elemental nozzles 12 and 13.

The zone at which the conduits for each rotor register with their chambers 61 is angularly adjustable to enable the amount by which this zone precedes the relative registration between successive pockets and the elemental nozzles to be adjusted. For this purpose the valve plates have limited rotation around the rotor axes. Rotation is effected by connecting rods 70 the small ends of which are connected to the valve plates at 71 and the big ends of which contain eccentrics 72. The eccentrics for the upper rods are on a longitudinal shaft 73 and those for the lower rods are on a longitudinal shaft 74, said shafts being supported by bores in the case 1 and by a bearing on the end cap 41. The shafts project from the end cap 41 and the projecting parts have handles 76 whereby the shafts can be rotated. Rotation of the shafts reciprocates the connecting rods and the rods oscillate the valve plates, thus enabling the position of the chambers 61 to be altered to the required degree.

Packing 80 held in place by clamping rings 81 is arranged around the reduced ends 18 of the rotors, said packing making sealing contact with the adjacent parts of the liner 8.

The projector is associated with a hopper, not shown, adapted to deliver material to be projected to the mouths 4 and 5. If it is desired to mix separate material and to project the mixture the hopper has a partition which registers with the web 1^a separating the mouths 4 and 5 and which separates the hopper into two compartments, one for one material and one for the other.

In use, the projector is supplied with the required pressure fluid or fluids by way of the control valve 40 and the worm 32 is driven. Driving the worm shaft causes the rotors to turn in the manner previously described. As the pockets 37 traverse the openings 9 and 10 they pick up material therein and as the ends of the conduits successively register with the chambers 61 the conduits and the pockets receive a charge of pressure fluid. The picked up material and the said charges are trapped in the pockets by the liner until they communicate with the elemental nozzles 12 and 13. Immediately this happens the pressure fluid is able to empty the pockets through the said nozzles, the said fluid mixing with the particles of the material in them. Each elemental nozzle, therefore, produces a jet of considerably greater length than width. Owing to the relative incidence of the nozzles 12 and 13 and to the fact that a pocket in each rotor registers with its elemental nozzle at the same moment as that with which a nozzle in the other rotor registers with its nozzle, the jets meet each other obliquely, long edge on, at the throat of the opening 11 and emerge therefrom and from the opening 6 as a single jet of sheet-like form.

Liquid if comprised in the opposed jets is partly atomised by being caused to issue from the nozzles 12 and 13 under pressure but the atomisation is completed and the resulting particles homogeneously dispersed and mixed throughout the volume of the combined jet owing to the collision of the particles relatively and to their relative bouncing. Similarly, when pulverulent or like material is projected, or a mixture of liquid and pulverised solid material, the solid particles col-

lide and bounce relatively and are mixed in a manner comparable with the way in which the liquid particles are caused to act.

The edges 2^a and 3^a of the openings 9 and 10 in the liner are sharp and so are the trailing edges of the mouths of the pockets 37. Thus, the said edges exert a shearing or scissor-like action on particles of fuel projecting from the mouths of the pockets. The width of the pocket mouths may be governed or adjusted so that particles of fuel over a predetermined size cannot completely enter the pockets and as a result of the said shearing action are reduced to smaller particles which can freely enter the said pockets.

15 The nozzles 12 and 13 may be so set relatively that they oppose each other directly. Their position may be fixed permanently or, if desired, they may be adjustable as to relative incidence, e. g., they may be in rotatable elements. The relative 20 setting of the nozzles is a factor determining the length of the final jet and is such as to suit the longitudinal dimension of the apparatus with which the projector is associated.

The median planes of the pockets 37 may be 25 radial. In order to keep the spaces between the rotors and their bearings clean the rotors may have bleed holes communicating with the said spaces and the bores through which the impellant passes on its way to the pockets.

30 In modifications of the projector shown the individual jets may directly enter the furnace or other chamber instead of previously combining in a chamber communicating with the furnace chamber or the like; the metal around the rotors, 35 or at least the metal around the rotors at the discharge zone of the pockets, may be so shaped (e. g., thin) as to have little or no influence in shaping the jets, the pockets then being the equivalent of elemental nozzles. The jets in this latter construction may meet in the throat of a main nozzle as 11 or may enter the furnace or other chamber directly.

The liner 8 may be made in two parts each 40 adapted to be turned around the axis of its rotor 45 whereby the angular position of the elemental nozzles and, therefore, the relative incidence of the jets, can be adjusted as required.

A single rotor projector may be constructed 50 from parts substantially as those described with reference to the drawing. That is to say a single rotor projector may comprise a case having a lined bore in which a rotor as 15 or 16 is located, valve means adapted to supply pressure fluid to the pockets and driving means for the rotor, the 55 rotor being a tolerance fit in the bore and the bore having an opening as 15 or 16 and a slot as 12 or 13. The slot as 12 or 13 may be located in any suitable position, for example, in the horizontal plane of the liner. The valve plates as 19, 20 60 may be adjustable as described with reference to the drawings and so may the liner.

What I claim is:

1. A projector for fluid materials comprising a cylindrical rotor in which are a number of 65 angularly spaced, longitudinal pockets, said pockets being adapted to receive the material to be projected, and valve controlled means for supplying fluid under superatmospheric pressure to each pocket in the vicinity of the end of each pocket toward the axis of the rotor and substantially throughout the whole of the length thereof when the pocket attains a predetermined position during turning of the rotor.

2. A projector for fluid materials comprising a 70 plurality of parallel rotors, each of said rotors

having a multiplicity of angularly spaced longitudinal pockets adapted to receive material to be projected, valve controlled means for supplying fluid under superatmospheric pressure to said pockets, and means for rotating said rotors so that the discharge of the contents of a pocket of each occurs simultaneously whereby the resulting simultaneously occurring jets impinge on each other.

3. A projector for fluid materials comprising a plurality of parallel rotors, each of said rotors having a multiplicity of angularly spaced longitudinal pockets adapted to receive material to be projected, means for rotating said rotors, valve controlled means for supplying fluid under superatmospheric pressure to pockets of each of said rotors to project the material in jets therefrom upon predetermined rotation of the rotors, said rotors being set to direct their jets in impinging directions and being so timed relatively that the discharge of the contents of a pocket of each occurs simultaneously whereby the resulting simultaneously occurring jets impinge on each other, and a main nozzle, the throat of said main nozzle being located at the zone at which the simultaneously occurring jets are arranged to meet.

4. A projector according to claim 2, comprising a pocket-shutting element around each rotor each of said elements having a longitudinal slot and being adapted to trap the contents of the pockets until the pockets register with the slot.

5. A projector according to claim 2, comprising a pocket-shutting element around each rotor each of said elements having a longitudinal slot and being adapted to trap the contents of the pockets until the pockets register with the slot and said slots being set to direct the jets in opposed directions.

6. A projector for fluid materials comprising a plurality of parallel rotors, each of said rotors having a multiplicity of angularly spaced longitudinal pockets adapted to receive material to be projected, means for rotating said rotors, valve controlled means for supplying fluid under superatmospheric pressure to pockets of each of said rotors to project the material in jets therefrom upon predetermined rotation of the rotors, said rotors being set to direct their jets in impinging directions and being so timed relatively that the discharge of the contents of a pocket of each occurs simultaneously whereby the resulting simultaneously occurring jets impinge on each other, and a main nozzle, the throat of said main nozzle being located at the zone at which the simultaneously occurring jets are arranged to meet, said main nozzle being shaped to impart a sheet-like form to the combined jet issuing from it.

7. A projector according to claim 2, comprising a pocket-shutting element around each rotor each

of said elements having a longitudinal slot and being adapted to trap the contents of the pockets until the pockets register with the slot, said elements being angularly adjustable.

8. A projector for fluid materials, comprising a cylindrical rotor, said rotor comprising a body, said body part having a number of angularly spaced longitudinal pockets and a like number of longitudinal conduits extending from end to end, the conduits communicating with the bottoms of the pockets, and valve plates at the ends of said body part, said valve plates having chambers with which the ends of the conduits successively register as the rotor turns, the chambers being adapted to be supplied with the pressure fluid and being provided with sealing means preventing escape of the said fluid from them between the valve plates and the ends of the said body part.

9. A projector according to claim 8, said sealing means comprising sealing cups arranged in the said chambers.

10. A projector according to claim 8 wherein the valve plates are adapted to be rotated, the rotation altering the position of the zone at which the conduits register with the chambers.

11. A projector according to claim 2 provided with a control valve for two kinds of pressure fluid, said valve being adapted to supply either fluid to both rotors or one fluid to one rotor and the other fluid to another rotor.

12. A projector according to claim 2, comprising a case, said case having two parallel longitudinal bores, said bores having linings, rotors in the linings, valve plates at the ends of the rotors and end plates adjacent the outer faces of the valve plates, said end plates carrying bearings for the rotors, fluid flow passages in the end plates for conveying pressure fluid to the chambers in the valve plates and sealing means (e.g. sealing cups 66) between the valve plates and the ends of said flow passages adapted to prevent the escape of pressure fluid between the valve plates and the end plates.
